UNITED STATES PATENT OFFICE.

URIAH SNYDER, OF CONSHOHOCKEN, PENNSYLVANIA.

IMPROVEMENT IN HORSESHOES.

Specification forming part of Letters Patent No. **144,483**, dated November 11, 1873; application filed February 21, 1873.

To all whom it may concern:

Be it known that I, URIAHS SNYDER, of Conshohocken, in the county of Montgomery and State of Pennsylvania, have invented an Improved Horseshoe, of which the following is a specification:

The object of my invention is to securely fasten detachable calks to horseshoes; and this object I accomplish, in the manner plainly shown in the perspective and sectional views of the drawing, by fitting the heel-calks B entirely around the ends F F of the shoe and against projections d of the same, and securing them thereto by means of wedges or split keys h driven into the space between the calk and shoe. The heel-calks B have an opening extending entirely through them, thus forming a strap or band, which passes around the end of the shoe when the calk is fitted to the same, as shown in Figures 1 and 3. The calk is rig-

idly secured to the shoe by means of a split key, h, Fig. 5, driven into the opening in the same; or, if desired, a simple wedge, retained by a set-screw, x, may be substituted for the split key, which is self-retaining; and the said calk is caused to bear against a projection, d, at the extreme end of the shoe, which, in conjunction with the wedge, insures its retention in the required position.

I claim as my invention—

The combination, substantially as described, of the heel-calk B, the end F of the shoe with its projection d, and the split key or wedge h.

In testimony whereof I have signed my name to this specification in the presence of two subscribing witnesses.

URIAH SNYDER.
